UNITED STATES PATENT OFFICE

93,772

DESIGN FOR A SAFETY EMBLEM

Eva J. Krieg and Archie T. Stromertz, San Jose,
Calif.

Application August 21, 1934, Serial No. 53,009

Term of patent 14 years

To all whom it may concern:

Be it known that we, **EVA J. KRIEG** and **ARCHIE T. STROMERTZ**, citizens of the United States, residing at San Jose, in the county of Santa Clara, State of California, have invented a certain new, original, and ornamental Design for a Safety Emblem, of which the following is a specification, reference being had to the accompanying drawing.

Figure 1 is a front elevation of a safety emblem embodying our design.

Figure 2 is a side elevation of a safety emblem embodying our design.

We claim:

The ornamental design for a safety emblem, as shown.

EVA J. KRIEG.
ARCHIE T. STROMERTZ.
